UNITED STATES PATENT OFFICE.

GEORGE A. TUCK, OF SAN FRANCISCO, CALIFORNIA.

GAS HEATING FURNACE.

Application filed June 22, 1925. Serial No. 23,804.

My invention relates to improvements in gas furnaces for heating purposes wherein a tortuous flue operates in conjunction with a combustion chamber and connections between said combustion chamber and the upper portion of said flue to facilitate a rapid upward movement of gases within said flue to prevent condensation; and wherein an air passage leading from the exterior of the furnace through the flue operates to absorb and convey a portion of the heat from said flue into the air heating passages of said furnace.

The primary object of the present invention is to provide a new and improved gas heating furnace.

Another object is to provide an improved device of the character described arranged to facilitate a rapid upward movement of gases within the flue to prevent condensation.

A further object is to provide new and improved means for first, quickly creating a rapid upward movement of gases within the flue to create or induce a high temperature; and then conduct a current of air from the exterior of the furnace, through a central passage within the flue to reduce the flue temperature and carry a portion of the heat from said flue back into the air-heating passages of the furnace.

I accomplish these and other objects by means of the device disclosed in the drawings forming a part of the present specification wherein like characters of reference are used to designate similar parts throughout the said specification and drawings, and in which—

Fig. 1 is a broken vertical sectional view of my improved gas furnace;

Fig. 2 is a detailed view of the dampers;

Fig. 3 is a transverse sectional view taken on line 3—3 of Fig. 1 in the direction indicated; and

Fig. 4 is a broken detailed view of the gas burners.

The present state of the art discloses gas furnaces having tortuous flues, one of the purposes of which is to retard the upward movement of gases through said flue in order to create a high temperature. The disadvantage of such an arrangement is a high condensation of the resulting moisture of

which very rapidly corrodes the metal portions of the furnace. Another disadvantage of such an arrangement is that after a draft has been created to carry the combusted and heated gases through the flue that a very high temperature is created within said flue and a great portion of heat is thus wasted through the said flue.

I overcome these disadvantages by first creating heat at a point within a tortuous flue which will rapidly facilitate and create an upward movement of the heated gases or products of combustion to prevent condensation and consequent corrosion of the metal parts of the furnace, and which will also create a high temperature within the flue, after which an air current is passed through a central pipe or passage within said flue to absorb and carry a portion of the heat from said flue into the air-heating passages of the furnace.

Referring to the drawings the numeral 1 is used to designate in general a furnace casing having the usual screened air intakes 2 at the bottom and hot-air conducting pipes 3 at the top thereof.

I employ preferably an annular combustion chamber or drum 4 within and in spaced relation to the casing 1 and an inner annular flue or drum 5 arranged within the central portion of the combustion drum or chamber 4 to provide air passages 6 surrounding and between said casing 1 and chamber 4 and also between said chamber 4 and the flue 5, the top and bottom of said flue 5 being preferably arranged above the top and bottom respectively of the combustion chamber 4, mainly to provide an enlarged air heating chamber within the central portion or core of said combustion chamber or drum 4.

The annular flue or drum 5 is provided with a central air space or portion 7, the purpose of which will hereinafter be more fully set forth.

The flue or drum 5 is provided with an annular baffle plate 8 arranged within the annular space thereof and in spaced relation with the bottom and top of the said drum or flue 5 and closed at the top of said plate 8 with respect to the outer wall of the drum or flue 5 whereby concentric outer and inner flues are formed to provide a tortuous

flue 9 through which the gases move downwardly in the outer concentric flue and upwardly within the inner concentric flue, the purpose of which will hereinafter be more 5 fully set forth.

Radial connections 11 connect the upper portion of the combustion chamber 5 with the upper portion and outer portion of the tortuous flue 9 and adjacent the top of the 10 baffle plate 8 whereby the upper portion of the baffle plate 8 and the said tortuous flue 9 will be quickly heated by gases passing from said combustion chamber 4 to the flue drum 5 as indicated by the heavy curved 15 arrows in Fig. 1 of the drawings.

The upper portion of the flue or drum 5 and above the baffle plate 8 is provided with a lateral flue 12 extending to the exterior of the furnace 1 and is provided with a vent or 20 draft opening 14 arranged to be opened or closed in varying degrees by means of a rotatably mounted sleeve 16 also provided with an opening 17 arranged to register with the opening 14 and thereby permit the passage 25 of air into the said lateral flue 12 and vertically disposed chimney flue 18 connected thereto.

Within the lateral flue 12 I have provided an air pipe or passage 19 extending throughout 30 the entire length of the lateral flue 12 and having an outer vent or opening 21 controlled by means of a suitable damper 22, the inner end of said pipe or passage 19 terminating within the central cylindrical air 35 space or core 7 of the inner flue drum 5, as disclosed in Fig. 1 of the drawings, in order that a draft of cold air may be drawn inwardly through said pipe or passage 19 by the upward movement or suction of heated 40 air within the air passages 6 of the furnace 1, and thereby absorb and convey a portion of the heat from the combusted gases moving through the flue into the interior of the furnace 1.

45 In the bottom front portion of the combustion chamber 4 I have provided a suitable door or opening 23 through which extends a preferably annular gas burner 24 which rests on the bottom of said combustion chamber 4.

This burner 24 is provided with a plurality of holes or jets 26 and is made preferably in two parts to facilitate introduction and manufacture of the parts. In order to 55 insure ignition of both parts from a double pilot burner 27 I have provided an intercommunicating burner 28 having a plurality of jet openings 29 in the upper portion thereof, said intercommunicating burner 28 connecting at both ends with both portions of the double burner, so that if, for any reason, the pilot 27 should light one side only of the double burner 24 the flame will be communicated, by means of said intercommunicating burner 28, to the other side of said 60 65

double burner 24 and thereby prevent an explosion.

In operation, assuming that the furnace is cold, when the burner 24 is lighted it will immediately heat the combustion chamber 4, 70 which in turn will heat the surrounding air passages 6, and the heated products of combustion will pass upwardly through the upper portion of said combustion chamber 4 and through the radial connections 11 and 75 be directed onto the upper portion of the baffle plate 8 and rapidly heat the same which heat will be quickly communicated to the air within the upper portion of the tortuous flue as represented by the inner 80 concentric flue 9. The heating of the air at this point will immediately tend to facilitate and produce an upward movement of air within the tortuous flue or passage 9, uniformly heating the metal drums and parts 85 of the furnace and preventing the formation of moisture through condensation, instead of retarding the upward movement of said combusted gases as in the present state of the art. 90

This upward movement of the combusted gases will immediately produce a high temperature within the flue and induce a powerful draft which will tend to carry considerable heat up the flue. To save this heat 95 and at the same time to reduce the temperature of the flue, the damper 22 is moved to uncover the opening 21 in the outer end of the air pipe 19 within the lateral flue 12. As the inwardly directed 100 current of air, which has been induced by the rising of the heated air within the furnace 1 and air passages 6 thereof, comes in contact with the heated pipe or air passage 19, a portion of the heat of said pipe 19 will 10 be absorbed and carried by said air current into the said air passages 6 within the furnace.

If it is desired to still further reduce the upward draft through the entire flue of the 11 furnace the same may be accomplished by rotating the sleeve 16 the required amount to uncover the opening 14 within the lateral flue 12 thereby admitting cold air into said flue, which will retard the upward movement 11 of gases within the tortuous flue and combustion chamber 4.

It is obvious from the foregoing that I have provided an improved gas furnace having a tortuous flue passage arranged to facilitate an upward movement of gases therethrough to quickly heat said flue and thereby obviate condensation and its resulting corrosion. 12

It is also obvious that I have provided improved means for absorbing and carrying a portion of the heat from the chimney flue back into the furnace thereby reducing the temperature of the chimney flue of the furnace, as well as means for regulating the tempera- 12

ture of said flue and also the degree of heat of the heated air within the air-heating passages.

Having thus described my invention what I claim as new and desire to secure by Letters Patent is—

1. In a gas furnace, the combination with a combustion chamber of a tortuous flue; and means connecting the upper portion of 10 said combustion chamber with the upper portion of said tortuous flue whereby heat from said combustion chamber may be directed against said upper portion of said tortuous flue to facilitate upward movement of 15 gases within said flue; air passages surrounding the combustion chamber and tortuous flue for conducting air to be heated; and means arranged within the upper portion of the flue for conveying an air current from a 20 point exteriorly of the furnace to the said air passages to absorb heat from said flue; and means for regulating controlling and adjusting air current.

2. In a gas furnace, the combination with 25 a combustion chamber of a tortuous flue; means connecting the upper portion of the combustion chamber with the upper portion of the tortuous flue whereby heat from said combustion chamber may be directed against 30 said upper portion of said flue to facilitate upward movement of gases therein; air passages surrounding the combustion chamber and tortuous flue for conducting air to be heated; means arranged within the upper 35 portion of the flue for conveying an air current from a point exteriorly of said furnace to said air passages to absorb heat from said flue; means for retarding upward movement of gases within the flue; and means for 40 regulating, adjusting and controlling said air current.

3. In a gas furnace, the combination with 45 an annular combustion chamber of an annular tortuous flue arranged within said annular combustion chamber to provide anular air passages between and surrounding said combustion chamber and flue; connections between the upper portion of said annular combustion chamber and the upper portion 50 of the tortuous flue and intercepting an annular air passage between said chamber and flue and arranged to direct heat from said upper portion of the chamber to the upper portion of the tortuous flue to facilitate upward movement of gases within said flue; means for admitting air into the upper portion 55 of the flue to regulate and control said upward movement of gases; means for conveying an air current from a point exteriorly of said furnace through the upper portion of the flue and into the annular air passages to absorb heat from said flue; and means for regulating and controlling said air current.

4. In a gas furnace, the combination of

an outer annular drum arranged to form a combustion chamber; an inner annular drum having a central air passage and arranged within the first mentioned drum to form an annular flue; an annular baffle plate arranged within the annular flue and arranged in spaced relation with the bottom of said annular flue and also arranged to form inner and outer parallel flues within 70 said drum, said baffle plate being closed at the top thereof with respect to the outer parallel flue whereby gases may be directed downwardly in said outer flue and upwardly within said inner flue; and connections between the outer combustion chamber and 75 the outer parallel flue and near the top of the baffle plate whereby heat from said combustion chamber will be directed against the top of said baffle plate to quickly heat and thereby facilitate upward movement of 80 gases within the inner parallel flue.

5. In a gas furnace, the combination of an outer annular drum arranged to form a combustion chamber; an inner annular drum having a central air passage and arranged within the first mentioned drum to form an annular flue; an annular baffle plate arranged within the annular flue and arranged in spaced relation with the bottom of said annular flue and also arranged to 90 form inner and outer parallel flues within said drum, said baffle plate being closed at the top thereof with respect to the outer parallel flue whereby gases may be directed downwardly in said outer flue and upwardly within said inner flue; and connections between the outer combustion chamber and 95 the outer parallel flue and near the top of the baffle plate whereby heat from said combustion chamber will be directed against the top of said baffle plate to quickly heat and thereby facilitate upward movement of 100 gases within the inner parallel flue; a lateral flue connected to the upper end of the inner parallel flue; and an air pipe mounted 105 within said lateral flue and connected with the inside of the inner annular drum to absorb and carry heat from said lateral flue into central air passage of said inner annular drum whereby a portion of heat from 110 said lateral flue may be carried into the interior of the furnace.

6. In a gas furnace, the combination of an outer annular drum arranged to form a 115 combustion chamber; an inner annular drum having a central air passage and arranged within the first mentioned drum to form an annular flue; an annular baffle plate arranged within the annular flue and arranged in spaced relation with the bottom of said annular flue and also arranged to 120 form inner and outer parallel flues within said drum, said baffle plate being closed at the top thereof with respect to the outer parallel flue whereby gases may be directed 125

downwardly in said outer flue and upwardly within said inner flue; and connections between the outer combustion chamber and the outer parallel flue and near the top of the baffle plate whereby heat from said combustion chamber will be directed against the top of said baffle plate to quickly heat and thereby facilitate upward movement of gases within the inner parallel flue; a lateral flue connected to the upper end of the inner parallel flue; and an air pipe mounted within said lateral flue and connected with the inside of the inner annular drum to ab-

sorb and carry heat from said lateral flue into the central air passage of said inner annular drum whereby a portion of heat from said lateral flue may be carried into the interior of the furnace; means for regulating and controlling the movement of gases through said flue; and means for controlling and regulating the passage of air through the air pipe within the lateral flue.

In witness whereof I hereunto set my signature.

GEORGE A. TUCK.
